BLASIUS BART, OF EAST ORANGE, NEW JERSEY.

REFLECTOR.

Original application filed September 23, 1921, Serial No. 502,679. Divided and this application filed
February 28, 1925. Serial No. 12,272.

My invention relates to an improved form of metallic reflector of the type now used in flash-lights, search-lights and similar light reflecting articles, and this application constitutes a division of my copending application on method of forming metal reflectors and apparatus therefor, Serial No. 502,679, filed Sept. 23, 1921.

There is a demand in the market at present for a form of reflector which can be manufactured cheaply and therefore with the use of a relatively small amount of material and with a minimum amount of labor. The manufacturing problem is further complicated by the requirement that such reflector be provided with a threaded socket for receiving the electric light bulb and some manufacturers of search-lights require an attaching flange or similar means for mounting the reflector in position in the frame or other support.

It has been suggested in applicant's copending application, Serial No. 387,974, filed June 10, 1920 and Patent No. 1,503,743 granted August 5, 1924 to form reflectors by spraying a solution of a silver salt onto a polished glass mold and to reinforce the thin film of reflecting metal by means of a backing of strengthening material such as copper, electrolytically deposited on the film of reflecting material while positioned on the mold. It is a vital requirement of this process that the glass mold be chemically clean and highly polished in order to properly receive the layer of reflecting material. This is particularly true when the material is nascently reduced silver.

Accordingly, one of the objects of the present invention is to provide for the formation of a reflector by practicing the method outlined with its necessity for a polished mold and at the same time form the required socket and attaching flange demanded by the search light manufacturer. This phase of the invention is attained by providing a glass mold in which the silver deposit receiving surface is continuous without projections and thus capable of being formed initially and also capable of being polished from time to time as is required by the practicing of the method outlined. Where the socket is to be formed the mold is provided with an opening extending therethrough and which of course does not interfere with the

polishing process. It will be understood that a mold provided with the necessary projections to form sockets, flanges and the like, would interfere with the polishing operation of the mold. The socket required is pre-formed preferably as a stamping from sheet metal, is positioned at the opening and incidentally constitutes part of the means for mounting the mold in position. With the mold held by means engaging the opening and with the socket located in position the suggested process of depositing the silver on the polished mold is practiced. Afterwards the mold with its silver deposit surrounding the socket is positioned in an electrolytic tank and in this case it is further suggested that the support of the mold constitute the conductor for carrying current to the mold. A layer of backening material, such as copper is deposited on the sprayed silver layer which copper deposit is continued across the socket, thus constituting a means for securing the socket permanently in place in the finished reflector. For the purpose of forming the attaching flange it is suggested that an outlining rim be demountably fitted to the previously polished surface of the mold and the electrolytically deposited backing be continued across the rim to form the required outwardly projecting fastening means.

Referring to the apparatus feature of the disclosure, an object of the invention is to provide a simple form of mold construction in which the different parts are readily demountable, particularly for the purpose of cleaning and polishing the glass mold which forms a part of the construction, and at the same time to provide a single piece of apparatus which can be utilized with its assembled parts during the act of depositing the reflecting material, and which can also be utilized to support and convey current to the parts of the electrolytic tank during the step of forming the backing layer.

Referring to the article of manufacture phase of the disclosure, an object of the invention is to provide a reflector which may include projecting parts, such as an electric light bulb mounting socket and a securing flange. It is also required that the reflectors be formed of a comparatively small amount of material; that all of the reflectors shall be uniform in appearance and that they be

constructed without necessity for any refined machining or expensive manual labor in the process of forming the same.

Referring to the accompanying drawings 5 there is disclosed a preferred embodiment of the physical aspects of the invention.

Figure 1 is a vertical sectional view taken axially through one of a set of mold structures showing the completed reflector in full 10 outline, after it has been rotated from its dotted line position in the electrolytic tank; and

Figure 2 is a sectional view taken axially through a finished reflector slightly modified 15 from the form shown in Figure 1 removed from the mold construction.

In the drawings, there is shown an electrolytic tank 10 containing an electrolyte 11 on which tank is positioned a combined mold 20 support and conducting rod 12. It is understood that in electrolytic work the tank is of some material length and the single support 12 has a plurality of mold structures positioned along the length thereof. These 25 structures are designed to be turned down into the electrolyte as shown in dotted lines or to be secured in their upright position shown in Figure 1 during the act of depositing the silver on the molds. However, a 30 usual practice is to mount the support 12 on a work table during the process of assembling the mold and depositing the silver on the same. A collar 14 is fixed to the rod 12 and is provided with a threaded bore 15 into 35 which is inserted one end of a brass plug 16, which projects laterally from the support 12. The plug is provided adjacent its opposite end with a stop shoulder 17 and the portion beyond the shoulder is screw threaded as 40 shown at 18. A semi-spherical hollow glass mold 19 is provided at its apex with an opening 20, of a size to receive the threaded end of the plug. The parts are so proportioned that the mold is disposed in position 45 with the part thereof surrounding the opening resting on the stop shoulder 17 and the mold is temporarily secured to the plug 16 by means of a cap or socket 21 screwed onto the portion 18 of the plug. The cap is provided 50 with an outstanding flange 22 which bears on the outer convex side 23 of the glass mold to force the same into engagement with the stop shoulder 17. The threaded socket 55 is preformed preferably by stamping from sheet metal and has a size and pitch of thread to accommodate whatever type of electric light bulb socket it is desired to screw into the completed reflector. The free edge 24 of the glass mold is outlined by a 60 rim 25 of non-conducting material preferably "bakelite". The inner periphery 26 of the rim is curved and shaped to snugly fit the glass mold and thus provide a closed joint between the glass mold and the bakelite rim. 65 The side 27 of the rim adjacent the metal

receiving portion of the mold has a width and is shaped to correspond to the width and shape of the securing flange desired on the completed article.

The device thus far described may be regarded as a complete reflector with a single lamp screwed into the socket at the apex of the same.

Under some conditions, such for instance, as where it is desired to mount a dim lamp 75 in the reflector an additional socket 29 is secured in place usually between the apex and periphery of the reflector. In order to show a form of cap different from the cap 21, the socket 29 is not threaded and is simply an open end tube. For the purpose of disclosing a means for securing either socket or cap in place by a means different from the plug 16 there is disclosed a bolt 30 passed through the mold and secured in place by a nut 31. The bolt is provided with a mushroom head 32 which bears at its central part on the outer end of the tubular lamp socket 29 and has a peripheral shoulder 33 which acts to prevent the copper backing from coming up to the top of the socket during the electrolytic depositing step of the method.

In this form of the lamp mounting it may be considered that the lamp is secured in the socket 29 in any usual manner, for instance, the socket may be the usual casing of the lamp bases now in general use.

The outer convex face of the glass mold is polished over its entire surface either manually or by means of a machine constructed for this purpose. It is appreciated that the surface of the mold polished is continuous and therefore is susceptible of being cleaned and polished without leaving re-entrance angles or other inaccessible portions. The polished mold is then positioned with the outer end of the plug extending through the opening, care being taken at this time that the polished surface is not touched by the hand of the operator, otherwise the silver deposit will not adhere to the touched parts. The threaded socket is screwed into position binding the mold against the stop shoulder and bringing the flange of the socket into bearing engagement with the polished portion of the glass mold surrounding the opening. The bakelite rim is then disposed in position and forced into snug engagement with the glass mold.

A mixture of silver salts and a reducing agent therefor is sprayed onto the exposed portion of the polished glass in the manner more particularly defined in the above identified applications. The silver deposit is continued up the threads of the flange on the socket and up to the flange forming the rim. When the desired thickness of silver deposit is formed the assembled structure is disposed in the electrolytic tank. Prefer-

ably the support 12, collar 15, plug 16, are formed of some conducting material such as brass and thus constitute a means for conveying current to the parts to be coated as is usual in electrolytic operations of this character.

It is appreciated that one homogeneous layer of backing material, such as copper, is formed and that this backing extends continuously and integrally across the rim to form the securing flange, across the silver deposit to reinforce the same and across the socket to secure the socket permanently in position relative to the reflecting surface in the completed reflector.

Having thus described my invention, I claim:

1. A concaved reflector provided at its apex with a threaded socket, the inner surface external to the socket defined by a thin layer of reflecting metal, a layer of backing metal defining the outer convex surface, extending continuously across all portions of the reflecting layer to strengthen the same and across the socket to secure the same in place.

2. A concaved reflector provided at its apex with a threaded socket constituting a sheet metal stamping, the inner surface external to the socket defined by a thin layer of reflecting metal, a layer of backing metal defining the outer convex surface, extending continuously across all portions of the reflecting layer to strengthen the same and across the socket to secure the same in place.

3. A concaved reflector including a pre-formed sheet metal socket, a layer of reflecting metal defining the concaved surface about the socket and a layer of electrolytically deposited copper defining the back side of the reflector, said copper layer constituting a backing for the reflector layer and for the socket.

4. A concave reflector including a pre-formed sheet metal socket, a layer of reflecting metal defining the concaved surface about the socket and a layer of electrolytically deposited copper defining the back side of the reflector, said copper layer constituting a backing for the reflector layer and for the socket and projecting beyond the reflector layer to form a securing flange.

5. A concaved reflector comprising three elements, a brass threaded socket, a silver layer defining the inner concaved face to the outside of the socket and a copper backing continuous over the convexed side of the silver layer and over the brass socket.

6. A concaved reflector comprising three elements, a brass threaded socket, a silver layer defining the inner concaved face to the outside of the socket and a copper backing continuous over the convex side of the silver layer and over the brass socket, said copper backing projecting beyond the sil-

ver layer to form an outwardly extending securing flange outlining the free edge of the reflector and formed integral with the backing for the silver layer.

7. A metallic reflector including a reflecting surface and provided with a lamp socket having the side thereof adjacent the reflecting surface substantially flush with the metal which forms said surface.

8. A metallic reflector including a backing layer, a layer of reflecting material, a lamp socket having the end adjacent the reflecting surface positioned in advance of the backing layer and secured in position by said backing layer.

9. A metallic reflector including a layer of reflecting material and a layer of a backing material, said reflector provided with a lamp socket secured in place coeval with the formation of the backing layer.

10. A parabolic reflector provided with a layer of reflecting material and a lamp socket positioned entirely in rear of the reflecting surface of said layer and exteriorly of the parabolic surface defining said surface and means electrolytically soldering the socket to the reflecting material.

11. A metallic reflector including a reflecting layer and a backing layer and a plurality of sockets secured to the backing layer and opening through the reflecting layer.

12. A metallic reflector substantially semi-spherical in form provided with a pair of preformed lamp sockets exposed from the reflecting surface of the reflector, one of said sockets being positioned at the apex of the reflector and a backing layer of electrolytically deposited metal securing the lamp sockets rigidly fixed in preset relative position.

13. A metallic reflector substantially semi-spherical in form provided with a pair of lamp sockets exposed from the reflecting surface of the reflector, one of said sockets being positioned at the apex of the reflector and adapted to accommodate a main lamp and the other socket being offset from the apex socket and adapted to accommodate a dimmer light and a backing layer for reflecting surface, said backing surface secured to the lamp sockets.

14. A metallic reflector provided with a layer of reflecting material, a preformed tubular member and a layer of metal electrolytically deposited on the reflecting layer and on said member to secure the same together while leaving the bore of the tubular member exposed through the layer of reflecting material.

Signed at East Orange in the county of Essex and State of New Jersey this 2nd day of February, 1925.
